UNITED STATES PATENT OFFICE.

GIUSEPPE PACI, OF NEW YORK, N. Y.

MACHINE FOR SHELLING GREEN PEAS AND BEANS.

SPECIFICATION forming part of Letters Patent No. 289,699, dated December 4, 1883.

Application filed January 6, 1883. (No model.)

To all whom it may concern:

Be it known that I, GIUSEPPE PACI, of the city, county, and State of New York, have invented a new and Improved Machine for Shelling Green Peas and Beans, of which the following is a full, clear, and exact description.

The object of my invention is to provide a new and improved machine for shelling green peas and beans.

Reference is to be had to the accompanying drawings, forming a part of this specification, in which the same letters of reference indicate the same or corresponding parts in all the figures.

Figure 1 is an elevation of my improved machine for shelling green peas and beans. Fig. 2 is a sectional elevation of the same. Fig. 3 is a plan view of the same, the top and funnel being removed. Fig. 4 is a plan view of the under side of the top disk, part being broken out. Figs. 5 and 6 are vertical central sections of the machine in planes at right angles to each other.

A circular frame, A, covered with wire-netting, or otherwise provided with perforations, is inclined downward slightly from the middle toward the edges, and is provided at the middle with a raised head, A', having curved sides. The screen A is also provided with a series of transverse bars or rods, A², on the upper surface, which rods break and open the pods and prevent them from being carried around unbroken. The top or cover B of the machine is above the frame or screen A, and to the under side of the top B is held a ring or disk, C, which is pressed toward the screen A by spiral springs C', attached to the under surface of the top B, and connected to the said ring C. The roughened or corrugated ring or disk is held to the under side of the top B by means of screws, rivets, hooks, or any other suitable device.

U is a rubber disk-face, ribbed and fastened to the under side of ring C, so as not to mash the peas or beans.

In the head A' of the screen A a movable plate, a, is placed, which is pressed outward by spiral springs a'. A hopper, D, is provided on the top B. The top B is suspended by means of arms b from a nut, E, rigidly mounted on a vertical shaft, F, on which is mounted a bevel cog-wheel, F', with which a

bevel cog-wheel, G, engages, which is mounted on the inner end of a horizontal shaft, G', provided at its outer end with a crank-handle, G², whereby the shaft F is adapted to be rotated. The shaft F passes loosely through the head A' of the screen A, which head A' is secured firmly, by a screw or otherwise, to a cog-wheel, H, which rests loosely on a collar, F², on the shaft F, and which beveled cog-wheel H also engages the beveled cog-wheel G, whereby the screen A will be caused to revolve in the direction opposite to that of the rotation of the top B and ring C, attached thereto. The circular screen A is above a receptacle, K, into which the shelled green peas or beans drop and slide down the inclined bottom of the same upon a conveyer-belt, L, which will be described hereinafter.

At the edge of the receptacle K a gutter, K', is formed, into which the pods of the peas or beans slide from the screen A, and into this gutter a prong, K², projecting from the edge of the screen A, passes.

From the bottom of the shaft F an inclined arm, m, projects upward and rests against the inclined bottom of the receptacle K, and in turning sweeps the shelled peas and pieces of pods mixed with or adhering to them out of the receptacle K through an opening in the same, and causes them to drop upon the conveyer-belt L, which passes over a pulley, M, at the bottom and a pulley, M', at the top, which pulley M is mounted on a shaft, M², provided at the end with a sprocket-wheel, n, over which a chain, O, passes, which passes over a sprocket-wheel, O', on the shaft G', and over a sprocket-wheel, P, on the shaft P', which extends through a cylindrical screen, Q, having meshes of different sizes, and provided below with a series of hoppers, R, R', and R².

Above the upper end of the conveyer-belt L a series of plates, S, is hinged on a shaft extending longitudinally above the upper roller, M', of the conveyer-belt.

A shaft, T, journaled in the machine-frame, is provided at its inner end with a beveled cog-wheel, T', engaging with the beveled cog-wheel F', and at its outer end with a fly-wheel, T², and a grooved pulley, o, over which a driving-belt passes, which also passes over a pulley, p², hung on the shaft of a fan or blower, W, at the lower end of the conveyer-belt L.

This belt is formed of a series of metallic sections jointed together, so as to form a surface sufficiently rough to cause the broken pieces of the pods to adhere thereto.

5 A scraper, M³, is attached to the frame of

into the hoppers or receivers R R' R², according to the size of the peas. A current of air is forced from the blower W upon the conveyor-belt L, and carries off the very fine particles of the pods. If, by chance, the peas are carried toward the scraper, M³, it
